(57) **CLAIM**

The ornamental design for an angle cut adjustable square head ground spike, as shown and described.

DESCRIPTION

FIG. 1 is a front view of an angle cut adjustable square head ground spike showing my new design.

FIG. 2 is a rear view of the angle cut adjustable square head ground spike.

FIG. 3 is a left side view of the angle cut adjustable square head ground spike.

FIG. 4 is a right side view of the angle cut adjustable square head ground spike.

FIG. 5 is a top view of the angle cut adjustable square head ground spike.

FIG. 6 is a bottom view of the angle cut adjustable square head ground spike.

FIG. 7 is a top perspective view of the angle cut adjustable square head ground spike.

FIG. 8 is a side view of the angle cut adjustable square head ground spike shown in FIGS. 1-7 with an alternate position of the handle.

FIG. 9 is a front view of an alternate embodiment of an angle cut adjustable square head ground spike.

FIG. 10 is rear view of the alternate embodiment of the angle cut adjustable square head ground spike shown in FIG. 9.

FIG. 11 is a left side view of the alternate embodiment of the angle cut adjustable square head ground spike shown in FIG. 9.

FIG. 12 is a right side view of the alternate embodiment of the angle cut adjustable square head ground spike shown in FIG. 9.

FIG. 13 is a top view of the alternate embodiment of the angle cut adjustable square head ground spike shown in FIG. 9.

FIG. 14 is a bottom view of the alternate embodiment of the angle cut adjustable square head ground spike shown in FIG. 9.

FIG. 15 is a top perspective view of the alternate embodiment of the angle cut adjustable square head ground spike shown in FIG. 9; and,

FIG. 16 is a side view of the alternate embodiment of the angle cut adjustable square head ground spike shown in FIGS. 9-15 with an alternate position of the handle.
